(57) **CLAIM**

The ornamental design for a light fixture, as shown and described.

DESCRIPTION

FIG. 1 is a perspective view of a light fixture showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view in an alternate state thereof, wherein the illuminating element is exposed.

The broken lines in the drawings illustrate portions of the light fixture that form no part of the claimed design. The dash-dotted lines in the drawings define the boundaries of the claimed design.
